UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

AUTOMATIC LOOM.

1,328,585.

Specification of Letters Patent. Patented Jan. 20, 1920.

Application filed September 14, 1917. Serial No. 191,405.

To all whom it may concern:

Be it known that I, JONAS NORTHRUP, a citizen of the United States, residing at Hopedale, in the county of Worcester and State of Massachusetts, have invented certain new and useful Improvements in Automatic Looms; and I do hereby declare the following to be a full, clear, and exact description of the invention, such as will enable others skilled in the art to which it appertains to make and use the same.

The present invention relates to an improvement in automatic weft replenishing looms.

In that type of automatic weft replenishing looms in which the filling is replenished, on the breakage or the predetermined exhaustion thereof, by the insertion of a filled bobbin or filling carrier in the active shuttle, the outer filling ends of the bobbins in the hopper are all attached to the hopper stud, as is known, so that the new filling may be held and therefore be properly laid in the shed on the first pick of the shuttle after the replenishing operation. When this strand of filling or weft has been beaten up against the fell by the reed and caught by the warps on the next shedding operation, there remains extending from the selvage to the hopper stud a part of the new filling, and this is known as the incoming filling end. Automatic looms are usually provided with a thread cutter located adjacent the selvage, for the purpose of severing the incoming filling end near the selvage so that it may not be caught up and woven into the shed, and thereby cause a double pick, which is a blemish in the cloth. It sometimes happens, however, that before the thread cutter, located adjacent the cloth selvage,—especially where this cutter is the usual temple thread cutter,—can operate to sever the incoming filling end that the latter is broken and is whipped into the shed. This breaking of the incoming filling end is commonly caused by the chafing of the filling by the top edge of the front wall of the shuttle box. It has been proposed heretofore to provide automatic looms with various devices to prevent this chafing and breaking of the incoming filling end by the front wall of the shuttle box. The object of the present invention is to provide an automatic

loom with an improved and simplified device for performing the same function, 55 namely to hold the incoming filling end in such position that it will not be chafed and broken by the shuttle box. To the accomplishment of this object, the invention consists in the automatic loom provided with 60 the improved incoming filling end support described in the following specification and particularly pointed out in the appended claims.

The preferred form in which it is contemplated embodying the invention is illustrated in the accompanying drawings, in which Figure 1 is a side elevation, partly in section, of the weft replenishing end of a loom showing the application of the improved incoming filling end support thereto; and Fig. 2 is a plan of the parts shown in Fig. 1, and, in addition, a plan of the loom temple.

The improved incoming filling end support of the present invention may be applied to any usual or preferred form of automatic weft replenishing loom in which the filling is replenished by the insertion of a filled bobbin or filling carrier in the active shuttle. 75 The loom illustrated in the drawings comprises a weft replenishing mechanism, of which the hopper is indicated at 5. The hopper 5 is provided with a vertically disposed groove 6 which receives the upright 80 7 of a bracket 8 secured to the breast beam 9. The hopper 5 is secured to the upright 7 by means of bolts 10. The weaving devices of the loom comprise a lay 12 mounted for swinging movements toward and from 85 the breast beam 9. The lay 12 carries the reed dents 13 which engage the filling or weft threads and beat them up against the fell of the cloth. On the end of the lay 12 which passes back and forth under the weft 90 replenishing mechanism, there is constructed the replenishing shuttle box, of which the back box plate is indicated at 14 and the top plate is indicated at 15. The front wall 95 of the shuttle box is shown at 16, and it is 100 the top edge of this front wall of the shuttle box which usually frays the incoming filling end so that it often breaks and is whipped into the shed before the thread cutter located adjacent the selvage operates to sever 105 it. The thread cutter in the loom illustrated

in the drawings is of the usual temple thread cutter type and is indicated at 18 in its usual place on the loom temple 19. The parts described above and their mode of operation are familiar to those skilled in the art.

The improved incoming filling end support of the present invention comprises a resilient rod 20 adjustably secured at its forward end to a bracket 22 fastened to the upright 7 by means of the lower bolt 10. The rear end of the resilient incoming filling end support rests on the top front edge 24 of the front of the shuttle box wall, as shown in dotted lines in Fig. 1, when the lay is at its rear center. When the parts are in these positions, the rear end of the resilient rod 20 rests in a notch 25 cut in the top of the front wall of the shuttle box. This is for the purpose of preventing the filling from catching on the rear end of the rod 20 as the filling passes out of the replenishing shuttle box on the first pick of the shuttle after the replenishing operation. Now the construction of the front wall 16 of the shuttle box and the top plate thereof is such that when the lay beats forward, and consequently the front wall of the shuttle box raises the resilient incoming filling end support 20, the latter is received over the top plate 15, as shown in full lines in Fig. 1. It is thus seen that as the lay beats backwardly and forwardly, the resilient incoming filling end support rises and falls, but that its rear end is always supported either on the top plate or on the top of the front wall of the shuttle box.

The operation of the improved incoming filling end support in holding the incoming filling end in such a position that it will not be chafed and broken by the front wall of the shuttle box, will be clearly understood from a consideration of the two figures of the drawings. It is assumed that there has been an operation of the weft replenishing mechanism and that the shuttle has completed its first pick through the shed and that the new filling has been beaten up against the fell by the reed. The incoming filling end will therefore be substantially in the position shown by the line 26 of Fig. 2, the filling end having passed out of the shuttle box when the lay was on its rear center. From this consideration of the drawings it will be seen that inasmuch as the outer end of the incoming filling end 26 is held by the usual hopper stud and the inner end thereof is held fast at the fell, and since the rear end of the resilient thread support 20 always rests on the shuttle box, that is to say, either on top of the front wall or on the top plate, the incoming filling end can never be engaged by the shuttle box, and therefore cannot be chafed thereby and broken before it is cut by the temple thread cutter.

Having thus described the invention, what is claimed as new is:

1. A loom having, in combination, a weft replenishing mechanism, a lay having a shuttle box at its replenishing end including a top plate and a front wall, and an incoming filling end support secured at its forward end to a fixed part of the loom, the rear free end of the support resting lightly on either the top plate or the front wall of the shuttle box during the backward and forward movements of the lay.

2. A loom having, in combination, a weft replenishing mechanism, a lay, a shuttle box thereon at its replenishing end including a top plate and a front wall, and an incoming filling end support fixed at its forward end, the rear end of the support being adapted to rest on the front wall of the shuttle box when the lay is at its rear center and to rest on the top plate when the lay is at its forward center.

3. A loom having, in combination, a weft replenishing mechanism, a lay, a replenishing shuttle box thereon including a top plate and a front wall, and resilient means fixed at one end and free to be moved at the other end for supporting an incoming filling end above the shuttle box during the backward and forward movements of the lay.

4. A loom having, in combination, a weft replenishing mechanism, a lay including a shuttle box at its replenishing end, a thread cutter located adjacent the selvage, and a resilient incoming filling end support fixed at its forward end and extending rearwardly to rest on the replenishing shuttle box to support the incoming filling end until the latter has been severed near the selvage by the thread cutter.

5. A loom having, in combination, a weft replenishing mechanism, a lay, a replenishing shuttle box thereon including a top plate and a front wall, a thread cutter located adjacent the selvage, and a resilient incoming filling end support fixed at its forward end and resting at its rearward end on the front wall of the shuttle box when the lay is at its rear center and on the top plate of the shuttle box when the lay is on its forward center, to support the incoming filling end and hold it from contact by the shuttle box until it has been severed by the thread cutter.

6. A loom having, in combination, a weft replenishing mechanism, a lay including a shuttle box at its replenishing end, and an incoming filling end support secured at its forward end to a fixed part of the loom, the rear end of the support resting on the shuttle box during the backward and forward movements of the lay.

7. A loom having, in combination, a weft replenishing mechanism, a lay having a shuttle box at its replenishing end including a front wall, and an incoming filling end

support secured at its forward end to a fixed part of the loom, the rear free end of the support engaging the front wall of the shuttle box during the movements of the lay.

8. A loom having, in combination, a weft replenishing mechanism, a lay having a shuttle box at its replenishing end, and an

incoming filling end support adjustably secured at its forward end to a fixed part of the loom, the rear free end of the support resting lightly on the shuttle box during the backward and forward movements of the lay.

JONAS NORTHROP.
